Geological cross-section diagram for Fig. 3a. The diagram shows a series of rock units stacked vertically. The top unit is labeled '22'. Below it are units labeled '20', '31', '22', and '20'. The next unit is labeled '31'. Below that is a thick, hatched unit labeled '64'. At the bottom are units labeled '21' and '28'. To the left of the diagram, there is handwritten text: 'Fig. 3a' at the top, followed by '10 26 31' and '74 22 20' on the left side, and '31 26 70' on the right side. There are also arrows pointing to the '22' and '20' labels.

UNITED STATES PATENT OFFICE.

JOHN GRUEN, JR., OF SPRINGFIELD, MISSOURI.

COMBINATION-DOOR.

1,314,959.

Specification of Letters Patent.

Patented Sept. 2, 1919.

Application filed April 29, 1918. Serial No. 231,445.

To all whom it may concern:

Be it known that I, JOHN GRUEN, Jr., a citizen of the United States, residing at Springfield, in the county of Greene and 5 State of Missouri, have invented certain new and useful Improvements in Combination-Doors, of which the following is a specification.

This invention relates to combined screen 10 and panel doors, and has for one of its objects to provide a simply constructed device which may be readily transformed into a screen door, a panel door, or a door having a transparent portion, without discarding 15 any of the parts or marring or disfiguring the door structure.

With these and other objects in view, the invention consists in certain novel features of construction, as hereinafter shown and 20 described and then specifically pointed out in the claim; and in the drawings illustrative of the preferred embodiment of the invention—

Figure 1 is a side elevation of a door constructed in accordance with the invention,

Fig. 2 is a transverse section on the line 2—2 of Fig. 1,

Fig. 3 is an enlarged vertical section of the upper portion of the improved door,

Fig. 3^a is a transverse sectional view taken on line 3—3 of Fig. 1.

Fig. 4 is an enlarged vertical section of the lower portion of the improved door,

Fig. 5 is a detached perspective view of a 35 storage casing or receptacle for the panel which for the time being is not in use.

The improved door comprises a frame or body formed with side or rail portions 10, a transverse head member 11, a transverse 40 base member 12, and one or more transverse intermediate members 13.

The space defined by the side members 10, the head member 11 and the intermediate transverse member 13 opens entirely through 45 the door, while the space defined by members 12—13 and the sides 10 is closed at one side by a permanent panel 14. At its upper edge the transverse member 13 is provided with a sill member 15, preferably projecting 50 beyond both faces of the door as illustrated in Fig. 2. The open space above the sill 15 is provided with a stop molding 16 entirely surrounding the open space, and including a portion attached to the upper face of the 55 sill member 15. Fitting within the space above the sill member at the inner face of

the door is an open stop frame represented as a whole at 17 and secured in place by suitable fastening devices 18. The frame 17 is of less thickness than the space between 60 the stop molding 16 and the inner face of the door, thus leaving a socket or seat for a sash frame 19 or 20 as the case may be. One of the sash frames, for instance the sash frame 19 is provided with a window pane of 65 glass or other like material represented at 21, while the other sash member 20 is provided with mosquito netting represented at 22, the sash members 19 and 20 are precisely alike and interchangeable, so that either the 70 screen or the glass supporting sash may be disposed between the holding member 17 and the molding 16. Formed in the lower edge of the intermediate member 13 is an upwardly directed seat indicated at 23, and directed upwardly from the base member 12 is a stop rib 24, the space between the upper edge of the stop rib 24 and the inner end of the seat 23 being slightly in excess of the vertical dimensions of the sash members 19 80 or 20. By this means the space defined by the stop rib 24, socket 23, the side members 10 and the filler panel 14 constitutes a storage pocket for the unused sash, which may be disposed with its upper edge in the seat 85 23 while its lower edge rests upon the stop rib 24 as shown in Fig. 2. The wall of the seat 23 next to the inner face of the door is inclined as shown in Fig. 2 to facilitate the insertion of the sash within the seat and in 90 position upon the stop rib 24, the latter having a finger receiving cavity indicated at 25 to enable the sash to be readily inserted and removed.

Formed at the sides of the pocket are 95 bearing shoulders or seats 26 and fitting within the space defined by the members 12—13 and sides 10 and bearing upon the shoulders 26 is a filler panel or door 27 to conceal the sash within the storage pocket. 100 The filler member 27 is preferably hinged at 28 to one of the side members 10 and provided with a suitable catch indicated at 29 at the side opposite to the hinges.

The hinges 28 and the catch 29 may be 105 transposed, if required, so that the closure panel 27 may be hinged to swing in either direction. The filler members 17 and 27 will conform to the general design of the door, so that the latter presents substantially the 110 same appearance as an ordinary door, and may be varied in design to any required

extent. A third member may likewise be provided similar to the panel 14, or with an opaque inner portion, so that the door can be arranged as an ordinary panel door, by 5 inserting the opaque member in the upper open portion instead of the glass or screen sash. A suitable receptacle represented at 30 in Fig. 5 will be supplied to hold the third unused panel.

10 Suitable packing strips 31 of rubber, felt or like material represented at 29, are inserted between the parts, where required, to prevent dust, moisture or cold air from passing.

15 Having thus described the invention, what is claimed as new is:

A door including side members top and bottom members and a solid intermediate transverse member, the lower edge of the 20 intermediate member being cut-away to form inner outer and intermediate horizontal

transverse stop shoulders disposed in stepped relation, a solid panel arranged on one side of the door and bearing against one of the outer stop shoulders, a movable panel pivotally mounted on the other side of the door and bearing against the other outer stop shoulder, said movable panel being spaced from the stationary panel to form an intermediate pocket adapted to receive a removable sash member, the wall of the pocket between the intermediate stop shoulder and one of the outer stop shoulders being inclined downwardly and laterally, and a stop rib seated in the bottom of the pocket and 35 forming a rest for the lower end of the removable sash member, there being a finger opening formed in the rib at substantially the center thereof and opening through the upper edge of said rib.

In testimony whereof I affix my signature.
JOHN GRUEN, JR. [L.S.]
